UNITED STATES PATENT OFFICE.

JOHN W. McMAHON, OF BOSTON, MASSACHUSETTS.

CURTAIN-ROD.

951,832.

Specification of Letters Patent. Patented Mar. 15, 1910.

Application filed May 6, 1909. Serial No. 494,406.

To all whom it may concern:

Be it known that I, JOHN W. McMAHON, a citizen of the United States, and resident of Boston, in the county of Suffolk and 5 State of Massachusetts, have invented new and useful Improvements in Curtain-Rods, of which the following is a specification.

My invention relates to the construction of rods for curtain draperies and the like 10 and has for its object the provision of a contrivance of this class which while susceptible of very cheap construction, may be at the same time strong and durable, of comely appearance, convenient to set up and take 15 down, and instantly adjustable to any width of window before which a curtain is to be suspended.

In addition to the above objects which I attain by my invention, I provide also an 20 adjustable curtain rod upon which two curtains may be suspended one behind the other.

In the drawings hereto annexed which 25 illustrate an exemplification of my invention,—Figure 1 is a perspective view of an extensible or adjustable curtain rod; Fig. 2 is a plan view of the same; and Fig. 3 is a view partly in cross section, taken on line 3 of Fig. 2 looking in the direction of 30 the arrow.

I provide brackets A which may be of the usual construction, that is to say, made by bending a strip of sheet metal, or which 35 may be of special construction as shown in Fig. 4 and provided with a downwardly offset chair portion A' in which the curtain rods and their fastenings may rest.

The curtain rod is doubled and is composed of two telescoping U-shaped members 40 B and B', the member B having an inside diameter sufficient to admit the member B' and to make a fairly free sliding fit therewith. The parallel portions of these U-shaped members will be conveniently close together so as to allow the free 45 passage of curtain rings if the same are used.

The fastening members are shown in the drawings as a bolt and nut construction, 50 the upper member C in this case being the

bolt member and the lower member C' being the nut member. The bolt head and the nut are in this case made spherical but obviously they may be made of any desired ornamental shape provided they be 55 of such size and configuration as properly to hold the rod members B and B' in place upon the brackets. The threaded bolt C² passes through an aperture at a (Fig. 3) and the nut C' is secured thereto being 60 screwed up until the bearing of the bolt head C upon the upper portion of the rod members is sufficiently tight to hold the rod members in place. The attachment of the rods to the brackets is therefore very simple; all that need be done is to lay the rods upon the brackets and then secure the fastening members. The curved ends of the double rods may, if desired, lie close to the fastening members and bracket, or each of 70 the rods may be so drawn out that the curved ends extend an appreciable distance on either side of the bracket fixture; thus with an arrangement of this character it is not necessary that the brackets A shall 75 be spaced apart a distance equal to the whole width of the space to be covered by the curtain. The curtains may hang wholly from the portions of the rods between the brackets A, or they may partly hang from 80 extending end portions of the rods if the securing of the latter to the brackets be as above suggested.

I am aware that double telescoping curtain rods and the like have been heretofore 85 known or used, but these have not to my knowledge been applied in the manner above described or with the conveniences resulting therefrom.

What I claim and desire to secure by 90 Letters Patent is:

1. In a curtain-hanger, the combination of brackets, double curtain rods, composed of a pair of U-shaped telescoping members, each provided with parallel arms, 95 which telescope with the parallel arms of the other, and fasteners to bind the telescoping members to the brackets.

2. In a curtain-hanger, the combination of brackets, double curtain rods composed 100

of a pair of U-shaped telescoping members, each provided with parallel arms, which telescope with the parallel arms of the other, and fasteners, passing through 5 the brackets between, and bearing on the upper surfaces of, the arms of the telescoping members.

Signed by me at Boston, Massachusetts this twenty eighth day of April 1909.

JOHN W. McMAHON.
